(57) **CLAIM**

The ornamental design for a bag-securing member for waste container, as shown and described.

DESCRIPTION

FIG. 1 is a top perspective view showing a first embodiment of a bag-securing member for a waste container showing my new design;

FIG. 2 is another perspective view thereof;

FIG. 3 is another top perspective view thereof;
FIG. 4 is a top plan view thereof;
FIG. 5 is a bottom plan view thereof;
FIG. 6 is a front elevational view thereof;
FIG. 7 is a rear elevational view thereof;
FIG. 8 is a right side elevational view thereof;
FIG. 9 is a left side elevational view thereof;
FIG. 10 is a perspective view showing a second embodiment of a bag-securing member for a waste container showing my new design;
FIG. 11 is a top plan view thereof;
FIG. 12 is a bottom plan view thereof;
FIG. 13 is a front elevational view thereof;
FIG. 14 is a rear elevational view thereof;
FIG. 15 is a right side elevational view thereof;
FIG. 16 is a left side elevational view thereof.
FIG. 17 is a perspective view showing a third embodiment of a bag-securing member for a waste container showing my new design;
FIG. 18 is a top plan view thereof;
FIG. 19 is a bottom plan view thereof;
FIG. 20 is a front elevational view thereof;
FIG. 21 is a rear elevational view thereof;
FIG. 22 is a right side elevational view thereof;
FIG. 23 is a left side elevational view thereof;
FIG. 24 is a perspective view showing a fourth embodiment of a bag-securing member for a waste container showing my new design;
FIG. 25 is a top plan view thereof;
FIG. 26 is a bottom plan view thereof;
FIG. 27 is a front elevational view thereof;
FIG. 28 is a rear elevational view thereof;
FIG. 29 is a right side elevational view thereof;
FIG. 30 is a left side elevational view thereof;
FIG. 31 is a perspective view showing a fifth embodiment of a bag-securing member for a waste container showing my new design;
FIG. 32 is a top plan view thereof;
FIG. 33 is a bottom plan view thereof;
FIG. 34 is a front elevational view thereof;
FIG. 35 is a rear elevational view thereof;
FIG. 36 is a right side elevational view thereof; and,
FIG. 37 is a left side elevational view thereof.

(Continued)

The broken line showing of a bag in FIGS. 1 and 2 is included for the purpose of illustrating environment and forms no part of the claimed design.

1 Claim, 22 Drawing Sheets
